W. G. HARTWIG

MERCURY TUBE SWITCH

Filed May 11, 1923

Inventor:

William G. Hartwig

By Rector, Hibben, Davis & Macauley
Atty's.

UNITED STATES PATENT OFFICE.

WILLIAM G. HARTWIG, OF CHICAGO, ILLINOIS.

MERCURY-TUBE SWITCH.

Application filed May 11, 1923. Serial No. 638,165.

To all whom it may concern:

Be it known that I, WILLIAM G. HARTWIG, citizen of the United States, residing at Chicago, in the county of Cook and State 5 of Illinois, have invented certain new and useful Improvements in Mercury-Tube Switches, of which the following is a specification.

This invention relates to mercury tube 10 switches adapted for use in closing electric circuits in response to changes in temperature in the room in which the switch is located and the present invention is a modification of that described and claimed in my 15 application, Serial No. 614,741 filed January 25, 1923.

The principal object of the invention is to provide improved means for automatically closing the circuit in case the mercury 20 tube is broken. A further object is to provide an improved arrangement of the metallic spring contacts adapted to be connected automatically upon the breaking or displacement of the mercury tube. A further object is 25 to provide an enclosed casing for the mercury tube having means for inspecting the mercury column and the contacts to be connected thereby. Other objects relate to various features of construction and arrangement which will appear more fully 30 hereinafter.

The nature of the invention will be understood from the following specification, taken with the accompanying drawings in which 35 one embodiment is illustrated.

In the drawings Fig. 1 shows a longitudinal section through the center line of the improved switch, Fig. 2 shows a front elevation of the switch with the cover thereof removed, Fig. 3 shows an elevation of the rear side of the switch, Fig. 4 shows a sectional view on the line 4—4 of Fig. 1 and Fig. 5 shows a sectional view on the line 5—5 of Fig. 2.

The invention comprises a supporting base 10 of insulating material which is oblong in shape and provided with curved extremities. This insulating base is enclosed in a sheet metal casing 11 which is stamped to form an 45 enclosure similar in shape to that of the insulating base, being provided with an upper wall 11^a and outer walls 11^b. The upper wall has an oblong opening 12 formed therein and an annular flange 13 extends upwardly around the edges of this opening to receive the edges of the lateral walls 14^a of

a sheet metal cover 14, which closes the opening 12 and forms a chamber 15 on the outer side of the base 10. Two sheets of fibre board or other insulating material 16 are mounted on the outer face of the base 10 and the ends of the base are provided with flanges 10^a of reduced thickness which are adapted to be engaged by the U-shaped metal clips 17. The inner arms of these clips are threaded to be engaged by screws 18 which pass through apertures in the casing 11 and in the cover 14, thereby securing both of these parts and the clips in rigid position with respect to the supporting base.

The outer arm 20 of the lower metal clip 17 is provided with a transverse, outwardly projecting flange 21, which extends through openings 22 in the insulating sheets 16, being provided with an opening 23 adapted to receive the bulb 24 of the mercury tube 25. The bulb 24 is frictionally engaged by a sheet metal gripping member 26 which is clamped around the bulb of the tube and provided with lateral flanges 27 adapted to engage notches 28 formed in the supporting flange 21 on opposite sides of the opening 23, as shown particularly in Fig. 5. The gripping member 26 is connected at 29 to a heat transmitting plate 30 which is provided with laterally extending arms 31 having a plurality of up-turned tongues 32 adapted to contact with the inner surface of the cover 14, so that a direct connection is established between the metallic cover 14 and the metallic gripping member surrounding the bulb 24 of the mercury tube. This construction causes the mercury column to respond readily to changes in temperature in the air surrounding the metallic cover. The arms of 90 the supporting flanges 21 are provided with tips 33 which are adapted to project between adjacent tongues 32, thereby holding the transmitting member 30 and the gripping member 26 against vertical displacement 95 within the chamber 15.

The mercury tube 25 is provided at suitable points along its length with metallic contacts 35 and 36 which extend through the tube into the vertical opening therein to be engaged by the mercury column when it rises to suitable heights. Rings of conducting material 37 are provided around the mercury tube at the points where the contacts 35 and 36 are connected, and conductors 38 and 39 lead from these contacts to the respective binding posts 40 and 41, which

extend through apertures in insulating sheets 16 and are mounted on the insulating base in cavities 42 provided for that purpose. The conductors 43 and 44, leading to the external circuit, pass through an opening 45 formed in the boss 46 on the under side of the insulating base and these conductors are connected to the binding posts 40 and 41, respectively, as shown particularly in Fig. 1.

In case the mercury tube becomes accidentally broken it is desirable that the electric circuit controlled thereby be closed so that the heating apparatus or other apparatus actuated by the circuit will be opened.

The terminal 40 is therefore provided with a metal clip 47 and the terminal 41 is connected to a metal clip 48. The clip 48 extends transversely beneath the mercury tube and is provided with a reversely bent resilient arm 48^a having a transverse projection 48^b adapted to rest on the outer surface of the mercury tube between the mercury tube and the cover 15. The projection 48^b engaging the mercury tube normally maintains the extremity 48^c of the resilient arm out of engagement with the metallic clip 47 but if the mercury tube becomes broken the projection 48^b is released and permits the arm 48^a to move inwardly toward the base 10 until the extremity 48^c engages the clip 47 and thereby establishes a connection between the terminals 40 and 41. The metallic clip 48 and its resilient arm 48^a are normally protected against accidental connection with the cover 18 by means of a curved sheet 50 of mica or other transparent insulating material which is mounted over the mercury tube with its edges inserted beneath the flanges 13 of the casing 11, as shown in Fig. 4. The inspection of the mercury contacts and the clips 47 and 48 through the transparent insulating sheet 50, is permitted by a glass window 51 which is secured in an opening 52 formed in the cover 15 by means of a metallic retaining member 53.

The metallic clip 17 at the upper end of the insulating base has an outer arm 55, similar to the arm 20 of the lower clip, and this arm is provided with a transverse flange 56 which extends outwardly through openings 57 formed in the insulating sheets 16. This flange is recessed as shown at 58 to receive bushing 59, formed of rubber or other suitable material, which is engaged by the mercury tube 25. The bushing is provided on its outer side with an annular groove 60 which engages the walls of the recess 58 on its inner side, and is engaged on its outer side by a retaining member 61, having the form illustrated particularly in Fig. 4. The extremities of the retaining member are pro-

jected inwardly at 61^a to be engaged by the reversely bent arms 62 which are formed on the supporting flange 55. The annular groove 60, formed in the bushing 59, has a greater width vertically than the thickness of the flange 56 and the retaining member 61. A loose frictional engagement is provided between the bushing 59 and the contacting parts so that relative movement is permitted and the frictional engagement of the mercury tube with the bushing 59 may also be slightly loose in order to permit a limited relative movement of the tube with respect to the bushing. This limited movement of the mercury tube which is thus permitted is adapted to insure the stability of the mercury tube regardless of any blows or vibrations which may be imparted to the supporting base or its casing. The manipulation of the mercury column to establish a circuit between the contacts 35 and 36 is thus prevented. The loose support of the lower end of the mercury column is adapted to cooperate with the frictional clip on the upper end thereof to bring about the desired result. The means herein described for supporting the mercury tube are claimed in my co-pending application Serial No. 614,741, filed January 25, 1923.

Although one form of the mercury tube switch has been shown and described for purposes of illustration, it will be understood that the invention may take various other forms without departing from the scope of the appended claims.

I claim:

1. A switch comprising a mercury tube, means for supporting said mercury tube adjacent each end thereof, a pair of contacts connected to said tube between said supports, a metallic clip connected to one of said contacts and provided with a resilient arm having a part engaging the outer side of said tube between said supports, and a second metallic clip connected to the other of said contacts and adapted to be engaged by said resilient arm upon breakage of said tube between said supports.

2. A switch comprising a mercury tube provided with a pair of tongue contacts to be connected by the mercury column, a pair of metallic contacts located outside of said tube and adapted to be connected upon breakage of said tube, a base for supporting said mercury tube, a metallic cover mounted over said tube and having a window therein opposite said contacts, and a sheet of transparent insulating material mounted within said cover over said metallic contacts.

WILLIAM G. HARTWIG.
